UNITED STATES PATENT OFFICE.

ALFRED M. LANE, OF ST. LOUIS, MISSOURI.

SCREEN FOR PIVOTED WINDOW SASHES.

Application filed April 29, 1920. Serial No. 377,577.

To all whom it may concern:

Be it known that I, ALFRED M. LANE, a citizen of the United States, and a resident of the city of St. Louis and State of Missouri, have invented a new and useful Improvement in Screens for Pivoted Window Sashes, of which the following is a specification.

This invention relates principally to pivoted window sashes or ventilators, and more particularly to the application of window screens thereto. The common method of screening windows with pivoted sash has been to cover the window opening with a basket screen, that is, a screen of semicircular form to accommodate the outwardly swinging lower half of the sash. The application of the basket screen is usually made from the outside of the building and necessitates the building of a scaffold to support the workmen and, therefore, is quite expensive. This form of screen also gives the building an unsightly appearance from the outside. The principal practical disadvantage of the above type of screen is the difficulty of making a tight joint between the adjacent meeting edges of the window screen and the swinging sash.

One of the principal objects of the present invention is to provide screens for windows of the swinging sash type which can be easily and cheaply applied and which will accommodate themselves to the swinging movement of the window sash and at the same time maintain a tight joint between the meeting edges of the sash and screen. Another object is to dispense with the use of separate fastening members for securing the screens in position and thereby minimize the time and expense of mounting and dismounting the screens. The invention consists principally in the improved manner of attaching the window screens to windows having pivoted sashes or ventilators, and it also consists in the combinations and arrangements of parts hereinafter described. In the accompanying drawings, which form part of this specification, wherein like symbols refer to like parts wherever they occur,

Fig. 1 is an interior side view of portion of a steel window frame having a horizontally pivoted sash or ventilator, a window screen mounting embodying the present invention being shown in connection therewith;

Fig. 2 is a vertical section through the

window, the section being taken through the middle portion of the window and screens on the line 2—2 in Fig. 1, the sash being shown partly open; 60

Fig. 3 is a notched vertical section taken through the middle portion of the sash, showing the hinged connection between the lower portion of the screen and the middle portion of the sash, the section being taken 65 on the line 3—3 in Fig. 1;

Fig. 4 is a horizontal section taken through the upper portion of the window frame, showing the manner of attaching the guide and retaining member for the upper screen; 70

Fig. 5 is a vertical section through the upper portion of the lower screen and the adjacent middle portion of the sash, showing the hinged connection between the upper edge of the lower screen and the sash; and 75

Fig. 6 is a view similar to Fig. 5 showing a modified means for closing the joint between the upper edge of the lower screen and the sash.

In the drawings, the invention is shown 80 in connection with a steel ventilator window unit 10 having a horizontally pivoted steel sash 11 of the type used for lighting and ventilating factories, office buildings and the like; but the invention is applicable to other 85 types of swinging windows having wooden frames and sashes.

The window frame 11 shown in the drawings comprises spaced horizontally and vertically disposed steel bars or mullions 12, 90 forming rectangular open spaces in which are fitted glass panes 13. The mullions are of T shaped section, forming rabbets in which the panes of glass are set. The side margins of the panes of glass are set in these rabbets 95 behind the head portions of the mullions with their edges located adjacent to the stem portions of the mullions and are held in this position, as by means of putty or clips. At their points of intersection, the bars or mullions are welded or otherwise secured together. A rectangular open space of the desired size is left in the frame and in this opening is mounted the sash 11. The middle portion of this sash is attached to the vertical bars of each side of the sash opening to swing in a vertical plane by means of 100 butt hinges 14, which are secured to the adjacent parts of the vertical frame and sash bars. One of the leaves of a hinge is secured 110 to the frame bar and the other leaf is secured to the adjacent sash bar, the two leaves

being held together by means of a horizontal pin or pintle.

The frame of the sash is made up of metal bars comprising top, bottom and side

5 rails 15, and the sash is divided into rectangular open spaces by horizontally and vertically extending mullions 16 of a shape similar to the mullions 12 of the frame 10. Glass panes 17 are set in these spaces and 10 are held therein in a manner similar to those of the frame openings. The top, bottom and side rails 15 of the sash are provided with flanges 18 which cover the joints between the top, bottom and side edges of the 15 sash and the adjacent bars of the frame and also act as stops to prevent the sash from swinging beyond its vertical position when closed. The flanges of the top and side rails on the upper half of the sash are located on the inner face of the sash, the side flanges terminating at a point above the 20 hinges 14, and the flanges of the bottom of the side rails of the lower half of the sash are located on the outer face of the 25 sash, the side flanges of the lower half terminating at a point below the hinges 14. The top, bottom and side rails of the frame are provided with inwardly projecting flanges 19 which are disposed on opposite 30 sides of the frame above and below the hinges, and act as stops for the sash and also close the joints between the sash and frame in a manner similar to the flanges 18 of the sash.

35 The upper screen 20 shown in the accompanying drawing has a metal frame of the kind shown and described in my Patent No. 1,350,027, dated August 17, 1920, and comprises frame members 21 and 22 and a mesh-work 23 locked therebetween. The upper screen is placed across the upper half of the sash opening on the exterior side of the frame. The upper screen has a hinge or mounting member 24 clamped between the 40 lower frame members 21 and 22 thereof. The hinge member 24 projects downwardly from the lower frame member of the screen and has a loop or beaded portion 25 at its lower margin. This loop portion is adapted 45 to cooperate with the groove or socket portion 26 of a similar mounting member 27, which is secured to the middle horizontal mullion of the sash by means of screws 28. The groove or socket portion of the mounting member 27 is not entirely closed, thus 50 leaving an open throat portion through which the loop or beaded portion 25 of the mounting member 24 may be inserted. The hinge members 24 and 27 extend the full 55 width of the screen, which is of slightly less width than the sash opening and its vertical dimension is of such length as to permit the upper edge thereof to extend beyond the upper end of the frame. When the lower 60 portion of the sash is swung outwardly, the

screen 20, by reason of its offset hinge connection with the sash, is lifted upwardly and its bottom portion is thrown outwardly a slight distance.

The upper end of the upper screen is held 70 against the top rail of the stationary frame and the space between the side margins of the screen and the side rails of the frame is closed when the sash is open by means of plates 30. These members also act as 75 guides for the screen during its upward movement and limit the outward movement thereof. The inner margins of the guide plates 30 are secured to the side rails of the frame by means of rivets 31 and extend 80 from a point above the sash pivots to the upper rails of the frame. The guide plates are offset inwardly toward each other to clear the head portion of the side rails of the sash opening and extend outwardly 85 therefrom. The plates are provided with retaining strips 32 of angular section, one flange of which is riveted or otherwise secured to the outer margins of the guide plates. The other flange projects inwardly 90 and laps the adjacent side margins of the screen. If desired, the outer marginal portion of the plates 30 may be flanged inwardly to take the place of the angle strips 32. The guide strips 30 are made wider at the 95 bottom than at the top, thereby leaving a greater space between the lower ends of the angle strips 32 and the frame at the bottom thereof than at the top to accommodate the outward movement of the lower portion of the screen when the sash is open. Thus, 100 when the sash is swung open, the upper screen will move upwardly between the guide plates and accommodate itself to the movement of the sash. The flanges of the guide and retaining strips are set at an angle which corresponds to the angle assumed by the screen when it is in its extreme open position.

The lower half of the sash opening is 110 covered with a screen 35. This screen is of similar construction to the upper screen 20 and is attached to the bottom rail of the sash by means of clips 36. The screen is of a width sufficient to enable the side margins thereof to extend beyond the side rails of the sash frame, and its upper edge terminates a short distance below the sash pivots. A hinge member 37 is clamped between the top frame sections of the screen 115 and has a curled upper marginal portion in the form of a bead 38. As shown in Fig. 5, the bead portion 38 of the hinge member 37 cooperates with a groove or socket portion 39 of a similar hinge member 40. The member 40 is disposed horizontally and extends inwardly and terminates flush with the inner surface of the sash panes. The hinge member 40 extends from side rail to side rail of the sash and its opposite end 120

portions are secured thereto by means of angle brackets 41. These angle brackets have their horizontal flanges secured to the ends of the hinge member 40 and have their vertical flanges riveted to the web portions of the side rails of the sash frame. The bead portion 38 of the hinge member 37 and the groove or socket portion 39 of the hinge member 40 are arranged in axial alignment with the horizontal sash pivots. With this arrangement, the space between the top of the lower screen 35 of the sash is closed during all positions of the sash, and no movement is imparted to the screen when the sash is opened by reason of the alignment of the bead and groove portions of the respective hinge members 37 and 40, the bead member 38 of the hinge member 37 merely rotating in the socket 39 of the hinge member 40 when the sash is swung open.

In the modification shown in Fig. 6, the space between the upper edge of the lower screen 35 and the sash is closed by means of an inclined metal strip 50. The lower end of this strip is clamped between the frame members of the screen, and its upper margin is provided with a bead 51 which presses against the sash panes. This strip is slotted to straddle the intermediate vertical mullion of the sash frame.

The invention admits of considerable modification without departing from my invention, and I do not wish to be limited to the exact construction shown and described.

What I claim is:

1. The combination with a window having a sash whose middle portion is pivotally mounted therein, of a screen for each half of the sash openings, one of said screens being arranged on one side of said window and the other screen being arranged on the opposite side thereof and hinges connecting the adjacent sides of said sash and each of said screens adjacent to the sash pivots for closing the space therebetween in all positions of said sash.

2. The combination with a window having a pivoted sash, of a screen for covering the sash opening, and a hinge connecting said sash and said screen adjacent to the sash pivots for closing the space therebetween in all positions of said sash, said connecting hinge comprising a member having a groove portion and a member having a bead portion adapted to fit into said groove portion, one of said members being secured to said sash and the other of said members being secured to said screen, whereby the difference of movement of said sash and said screen is accommodated and a closed space between the adjacent portions of said sash and said screen is maintained in all positions of movement of said sash.

3. The combination with a window having a pivoted sash, of a screen for covering the sash opening, and a connection between said sash and said screen adjacent to the sash pivots for closing the space therebetween in all positions of said sash, said connection comprising a member having a groove portion and a member having a bead portion adapted to fit into said groove portion, one of said members being secured to said sash and the other of said members being secured to said screen, whereby the difference of movement of said sash and said screen is accommodated and the space between the adjacent portions of said sash and said screen is kept closed in all positions of said sash, and a guide strip secured to said window and engaging said screen to retain the same in position.

4. The combination with a window having a sash whose middle portion is mounted therein to turn on horizontal pivots, of a screen for the upper half of said sash opening, said screen being arranged opposite the upper half of said sash opening with its upper edge terminating above the upper edge of said sash opening when said sash is in closed position and with its lower edge terminating a short distance above the sash pivots when in said position, a connection between the lower edge of said screen and the adjacent portion of said sash for covering the space between said sash and screen in all positions of said sash, said connection comprising a member secured to the sash having a socket portion and a member secured to said screen having a bead portion fitting into the socket portion of said first mentioned member, and a guide strip secured to the window at each side of the screen and having a portion lapping the side margins of said screen to retain the same in position.

5. The combination with a window having a sash whose middle portion is mounted therein to turn on horizontal pivots, of a screen for the upper half of said sash opening, said screen being arranged opposite the upper half of said sash opening with its upper edge terminating above the upper edge of said sash opening when said sash is in closed position and with its lower edge terminating a short distance above the sash pivots when in said position, a connection between the lower edge of said screen and the adjacent portion of said sash for covering the space between said sash and screen in all positions of said sash, said connections comprising a member secured to the sash having a socket portion and a member secured to said screen having a bead portion fitting into the socket portion of said first mentioned member, a guide strip secured to the window at each side of the screen having a portion lapping the side margins

of said screen to retain the same in position, a screen for the lower half of said sash opening, and a connection between the upper edge of said screen and the adjacent portion of said sash for covering the space between said screen and said sash, said connection comprising a member secured to said sash and having a socket portion dis-

posed in axial alinement with the sash pivots and a member secured to said screen ¹⁰ having a bead portion fitting into said socket.

Signed at St. Louis, Missouri, this 22nd day of April, 1920.

ALFRED M. LANE.
